US00D608115S

(12) **United States Design Patent**
Trinh et al.

(10) **Patent No.:** **US D608,115 S**
(45) **Date of Patent:** **** Jan. 19, 2010**

(54) **DISPLAY APPARATUS**

(75) Inventors: **Nick Quang Trinh**, Minneapolis, MN (US); **Jeffrey P. Pirro**, Marcellus, NY (US); **Matthew W. Farrell**, Syracuse, NY (US)

(73) Assignee: **Target Brands, Inc.**, Minneapolis, MN (US)

(**) Term: **14 Years**

(21) Appl. No.: **29/344,010**

(22) Filed: **Sep. 22, 2009**

(51) **LOC (9) Cl.** **06-04**

(52) **U.S. Cl.** **D6/477**

(58) **Field of Classification Search** D6/464, D6/449, 455, 457, 470-472, 474-475, 477, D6/567; 108/107, 144.11, 149, 59, 161, 108/108; 312/107, 114; 211/59.4, 134, 69, 211/186-192

(74) *Attorney, Agent, or Firm*—Fish & Richardson P.C.

(57) **CLAIM**

The ornamental design for a display apparatus, substantially as shown and described.

DESCRIPTION

FIG. 1 is a perspective view of a display apparatus.

FIG. 2 is a front elevation view of the display apparatus of FIG. 1.

FIG. 3 is a rear elevation view of the display apparatus of FIG. 1.

FIG. 4 is a right elevation view of the display apparatus of FIG. 1.

FIG. 5 is a left elevation view of the display apparatus of FIG. 1.

FIG. 6 is a top plan view of the display apparatus of FIG. 1; and,

FIG. 7 is a bottom plan view of the display apparatus of FIG. 1.

The broken lines are for environmental purposes only and form no part of the claimed design.

1 Claim, 5 Drawing Sheets
